BY
Wm. H. Campbell,
ATTORNEY.

UNITED STATES PATENT OFFICE.

RAYMOND S. FOW, OF NEWARK, NEW JERSEY, ASSIGNOR, BY MESNE ASSIGNMENTS, TO BREEZE CORPORATIONS INC., OF NEWARK, NEW JERSEY, A CORPORATION OF NEW JERSEY.

CRANE.

Application filed June 10, 1927. Serial No. 197,818.

This invention relates to an improved crane for use over a restricted central space and is particularly adapted for repair work on automobiles, as one man can remove, 5 replace or adjust heavy parts that at present require the services of several men.

The device is constructed so that it can be supported on the side frames of a chassis and thus bridge the chassis and it can be 10 made compact enough to fit under the cowl of an automobile. This position enables it to be used for lifting the transmission on automobiles or tractors, for lifting the front of motors for changing timing gears, for 15 removing or replacing fly wheels on motor cars without removing the motors, for pulling out and replacing worm drives in cars, and for other uses in this connection.

In handling some parts, as in seating 20 transmission cases, the placing requires a forward and rearward adjustment in fitting the parts, and the device is, for this reason made so that the hoisting means has a limited movement in a direction longitudinally of the car, that is, laterally relative to 25 the crane.

The invention is illustrated in the accompanying drawing, in which Figure 1 is a 30 face view of a crane made according to my invention and Figure 2 is a side view thereof.

The device is made of a main frame which is arched and I show a frame made in the form of a shear with the shear legs 10 and 35 11 pivoted together at the top, as at 12. The bottoms of the shear legs are adapted for securing to the side bars 13 of a chassis and the form illustrated shows slotted clamps 14 secured to the bottoms of the 40 shear legs. At least one of these clamps is pivoted to its leg although I show both clamps so pivoted at 15. The pivoting allows the aligning of the slots 16 of the clamp with the chassis bars 13 in the various 45 widths of cars. The clamping is done by suitable means such as the screws 17.

The shear is supplied with a suitable hoist and I illustrate the cable 18 with a suitable grappling device 19, the cable passing over the pulley 20 and raised or lowered by the drum 21 operated by a handle 22. A ratchet 23 secured to the drum and a pawl 24 secured to the arm 11 hold the drum in position. The grappling device 19, is, of

course, of various kinds to meet the requirements of the job and to conform to the parts to be elevated.

The cable and the pulley 20 are usually supported to allow a lateral or side movement of these parts, and I show a clevis 25 on the shear, the shaft 26 being supported thereby and the pulley being slidable on the shaft. The clevis is wide enough to allow a material sliding of the pulley thereon.

The crane can thus be used for not only raising and lowering parts of the engine mechanism but also for moving them forward or back to fit them together when such movements are necessary.

The device is compact and permits one man 70 to lift elements weighing many hundreds of pounds which at present require the services of two or three men.

In the drawing the dotted outline indicate a transmission case at 27 and a part of 75 a cowl of an automobile at 28. The usual size of the device is of such dimensions as to allow it to be easily inserted under the cowl of a passenger car or a truck.

It is usual to attach the pulley 20 and its 80 supporting means to one of the shear legs rather than to the pivot so that the suspending part of the cable 18 is central of the shear, therefore, it is in the centre of the chassis frame which is the position of most 85 of the parts that require adjustment. This, however, does not interfere with the use of the crane on elements to one side of the centre.

I claim:—

1. A crane for use on automobiles comprising a pair of hinged shear legs that are curved to fit under the cowl of the automobile, means on the ends of the legs for securing them to the chassis of a car, and a 95 hoisting mechanism on the shear.

2. A crane for use on automobiles comprising an arched frame with slots on the outer sides at the bottom of the arch said slots to embrace the inner sides of the chassis of the automobile, and a hoisting and holding means secured to the crane.

3. A crane for use on automobiles comprising a pair of hinged shear legs having slots on the outer sides at the bottom, means for 105 clamping the frame of the chassis in said slots, a pulley suspended from one of said legs, a hoisting cable passing over the pulley,

a pawl and ratchet for holding the cable and a handle on the ratchet.

4. A crane for use on automobiles comprising a pair of hinged shear legs having 5 slots on the outer sides at the bottom, means for clamping the frame of the chassis in said slots, a pulley suspended from one of said legs, the suspending means of the pulley allowing a limited side movement of the 10 pulley, and a hoisting cable passing over said pulley for the raising of elements of the car mechanism between the chassis frames.

5. A crane for automobiles comprising 15 a pair of shear legs hinged together at the

top, a clamp secured to the bottom of each leg at least one of said clamps being pivoted to its leg, and a hoisting means supported by and between the shear legs.

6. A crane for automobiles comprising a 20 pair of shear legs hinged together at the top, a clamp secured to the bottom of each leg, at least one of said clamps being pivoted to its leg, a pawl and ratchet on one of said legs, a handle for operating the ratchet, a 25 cable operated by the handle and a pulley on the crane over which the cable passes.

In testimony whereof I affix my signature.

RAYMOND S. FOW
